United States Patent Office

Des. 185,626
Patented July 7, 1959

185,626

TABLET DISPENSER

Burnie M. Craig, Pasadena, Thomas K. Hale, Glendale,
and Henry C. Keck, Pasadena, Calif.

Application November 17, 1958, Serial No. 53,391

Term of patent 14 years

(Cl. D52—2)

Des. 185,626

PAGE 2

Fig. 1 is a perspective view of a tablet dispenser showing our new design.

Fig. 2 is a rear elevational view thereof.

Fig. 3 is a sectional view thereof taken through line 3-3 of Fig. 2.

Fig. 4 is a sectional view thereof taken on line 4-4 of Fig. 2.

The dominant features of the design reside in the portions shown in full lines.

We claim:

The ornamental design for a tablet dispenser, substantially as shown and described.
